UNITED STATES PATENT OFFICE

PAUL W. CURTIS, OF DALLAS, TEXAS, ASSIGNEE TO TRAY SERVICE COMPANY, OF DALLAS, TEXAS, A CORPORATION.

PORTABLE SUPPORT DEVICE.

Application filed December 31, 1928. Serial No. 158,379.

This invention relates to portable support devices, and especially to support frames for attachment to various articles, and more especially to various kinds of shallow receptacles such as serving-trays, and to which they may be fixed detachably or permanently as may be desired.

I have disclosed in this invention a structure which is very suitable for supporting an article upon the upper edge of a vertical wall such as the door of an automobile, though it is by no means limited to such use. It has long been considered an advantage to provide a device for meeting these conditions, and include therein as one of its features, a member which may be adjustable upon the supporting frame for bracing the latter adjustably against the wall upon which it will rest when in operation, so that it may vary the angle of inclination to such wall and yet make very positive the position of the frame and at the same time make feasible the convenient and practicable stacking of a large number of such frames in a vertical pile, when not in use.

It is a further object of my invention to provide an especially strong brace member, though light in weight, for adjustable positioning of the receptacle or other article on said wall, and especially strengthening said brace member by making the same of integral metal strips extending lengthwise of the member and at an angle to each other.

With these and other objects of my invention contemplated in this disclosure, I have described in detail the structure found most practicable, in the specification hereunto attached, recited in the appended claims, and illustrated in the accompanying drawings, in which—

Figure 1 is a view in perspective, of a frame structure designed for detachable connection with an article to be supported upon a vertical wall;

Figure 2 is a side elevation of such frame and a receptacle held therein;

Figure 3 is a side elevation of a plurality of such frames and trays stacked in vertical alignment;

Figure 4 is a rear elevation of the structure shown in Fig. 2;

Figure 5 is a perspective of a brace member, and Figure 6 a sleeve member designed to be attached to the brace member of Fig. 5;

Figure 7 is a perspective view of the attached sleeve and brace members together with an elongated bar upon which the sleeve may be adjusted;

Figure 8 is an inverted plan view of my detachable frame structure shown applied to the bottom of a receptacle;

Figure 9 shows a perspective view of brace and head connection designed to serve as a modification of the form of structure shown in Fig. 7;

Figure 10 is a detail view of the brace member of the form in Fig. 9, a portion of the member being shown in dotted lines in collapsed position, but in full lines in operative position;

Figure 11 is a transverse sectional view of the hollow bar of Figs. 9 and 10, on the line 11—11 of Fig. 9;

Figure 12 is a similar section taken on the line 12—12 of Fig. 9;

Figures 13 and 14 are detail views in perspective, of a modified form of the adjusting sleeve and the brace member, respectively;

Figures 15, 16 and 17 are views of still another form of the sleeve and brace member, 15 being a perspective, 16 a transverse section in operative, and 17 such section in collapsed position of the parts;

Figure 18 is an inverted plan view of the frame structure and attached parts, the brace member being shown in collapsed position and latched in such position to the frame;

Figure 19 is a detail view of the latch and associated parts, on a greatly enlarged scale, but of the form shown in Fig. 18;

Figure 20 is a perspective view of the upper end of another form of brace member;

Figure 21 is a perspective view of the same form of brace member as that in Fig. 20, but in full length, and also showing in dotted lines the bar used with this brace;

Figure 22 is a perspective view of a detachable frame and adjustable brace member, there being but three engaging parts for the receptacle used in this form, but otherwise being quite similar to the form shown in Figs. 1 and 2, and

Figure 23 is an inverted plan view of a frame designed to be secured permanently to the bottom of the receptacle on which it is to be used, the brace member being adjusted on the brace bar as in the detachable forms.

In the drawings, an article, illustrated as

an open receptacle 5, is to be supported detachably on the upper edge of a wall or other plate at an angle to the horizontal, and designated in Fig. 2 in dotted lines as 5 a vertical wall, such as a vehicle wall 6 as of a door. The receptacle may well be one for serving refreshments to guests, and is shown in Figs. 2, 3, 4, 8 and 23, as a tray 7. In Figs. 1 to 22, inclusive, the frame is detachable from the receptacle, and the frame 8 is shown in Figs. 1 to 4, 8 and 18, as provided with two pairs of spaced flexible hooks 9 for engaging the beads 10 of the upper edge of the trays.

15 The hook members 9 are supported on spaced and bent ends 11 of bars 12, the latter being held in spaced position from each other by spaced bars 13 at right angles to 12 and ordinarily riveted or otherwise attached thereto. The lower ends 14 of the hooks 9 are bent slightly outwardly from the main portion to be in substantial parallelism with the bent ends 11 of 12. The upper ends of the hooks 9 are curved and bent inwardly somewhat, as at 15, to serve as a convenient attaching means for engagement with the beads 10. These hooks 9 are designed to engage the tray edge positively, but are sufficiently flexible to yield outwardly enough to make ready detachable engagement with the tray to be engaged or disengaged therefrom.

Attached to the lower faces of the bars 13, as shown in Figs. 1 to 4, 8 and 18, is a hollow bar 16 intermediate the bars 12. This bar 16 is ordinarily made from sheet metal whose edges are bent over into opposing position but not quite meeting each other leaving a space therebetween resulting in a 30 slot 17 extending almost the entire length of the bar 16. In Figs. 1 to 4 and 8, the slot faces upward adjacent the bottom surface of the receptacle 5, but in Fig. 18, it faces downward for another reason. This construction of the clamping bar 16 as shown in these views, enables the manufacturer to make use of sheet metal for his purpose and at the same time provide a relatively thick finished bar, a desideratum of great 40 value, as will be seen in later consideration of details of construction.

I make use of a very positive clamping action of bar 16 by means of a lever clamp 18 shown in Figs. 1 to 5, 7, 8, 14, 22 and 23. 55 In such construction, the lever clamp is formed of the lateral-flanged bar type, with the upper end hinged to a sliding sleeve enclosing the stationary bar 16 or its equivalent. In Fig. 6, is shown a typical form of 60 such sleeve 19, in which a main flat portion 20 is provided, usually of sheet metal, and lateral flanges are bent in parallelism finally resulting in four spaced portions, two of them 21 being apertured at 22 to receive 65 a pin therethrough and the other two 23

bent towards each other at 24 to form an effective enclosing collar within which the bar 16 may be held in adjustment.

The side flanges of the lever 18 may well be widened at 25 where the upper end of 70 the part 18 is pivoted to the sleeve 19, the flanges 25 being also apertured at 26 to align with the apertures 22 of the sleeve, and a pin 27 may then be inserted through the several apertures of the parts whereby 75 the lever 18 is not only mounted hingedly upon the sleeve flanges 21, but may be so mounted that the upper edge 28 of the flat bar 29 of 18 will contact the lower face of the cross bar 16 while the lever 18 is still in 80 oblique position, as shown in Figs. 1, 2 and 22. Fig. 7 also shows such relation of parts 16 and 18, and makes the more evident that lifting the lower or toe part 30 of the lever will release the lever from its clamping ac- 85 tion on the cross bar 16.

One pair of the ends 14 of the hook members 9 normally engages the upper edge of a vertical wall, as 6, while the receptacle is to be detachably mounted on said wall, the toe 90 30 of the lever 18 engaging the wall surface beneath the receptacle, and at a point that will enable the lever 18 to act efficiently as a brace member to retain the receptacle 5 in an approximately horizontal 95 position. Evidently, the sleeve member 19 may be readily adjusted lengthwise of the bar 16 to make certain the proper position of the edge 28 in clamping the bar itself just at the rear of the sleeve. This clamping mechanism may therefore accommodate itself to walls of different thickness, of slightly varying surface shape, and even to walls of different angular position, the position of the sleeve 19 on the bar 16 determining the final position of the receptacle 5 on the wall. 100

In the form shown in Figs. 13 and 14, the sleeve 19^a has the parts 20, 23 and 24 like those of the sleeve 19, but instead of the flange members 21 of the first form with the apertures 22 therein, 19^a is provided with longer flange members 21^a having near their ends inwardly-bent circular portions 31 that resemble cup parts without apertures 115 therein, and which are adapted to engage similar cup-shaped sockets 32 in the upper portions of the lateral flanges 25^a of the modified lever 18^a, and thereby pivot the lever upon the sleeve of this modified form 120 without a pin construction. The parts 28 and 29 of this lever are substantially like the corresponding structure of the first form.

In Figs. 9, 10, 11 and 12, is shown a still different form of clamp structure involving changes in the lever and sleeve parts only, and which will now be described. For the clamping bar 16 is substituted another hollow bar 33 formed of sheet material whose edges are not bent directly toward each oth- 125 130

er, as in the first form, but laterally for a small distance and then downward at 84 in an oblique direction until the edges 85 are almost in contact leaving a small slot 86 therebetween, as shown very clearly in Figs. 9 and 11. In this form of clamp structure, the relation of the sleeve and lever parts, shown in Fig. 7, to the clamping bar 16, as one having the sleeve 19 sliding outside the bar 16, is reversed. In this modified form in Figs. 9 to 12, the lever part 37 is solid, and provided with a solid flat head 38 designed to slide within the hollow bar 33 rather than outside, and for purposes of latching the parts in adjusted position, the part 37 is pivoted to the lower flange 39 extending integrally from the head 38, the pivot 40 being longitudinal of the head. This permits the lower extent of the lever 37 to be swung laterally on said hinge 40 under certain conditions. The edges 35 of the bar 33 extend normally down somewhat below the hinge 40, and thereby prevent the pivoting of the lever 37 while the head 38 may be moved lengthwise of the bar 33. But for a limited distance, one of the bent edges 34 is cut away, as shown at 41 in Figs. 9, 10 and 12, to permit the rocking of the lever laterally into said space 41 and thereby lock the head in a positive position and also permit folding the lever for purposes of readily stacking the receptacles in the manner shown in Fig. 3. The ends of this bar 33 may be attached to the frame bars 13 just as in the other form formerly described.

In Figs. 15, 16 and 17, another form is shown, the clamp bar 42 is substantially circular in cross section, has a slot 43 therein and the latter provided with a cut-out portion 44 to permit rocking laterally of the lever 45 whose cylindrical head 46 is integral with the lever 45, there being no need of pivoting of the parts when the parts are circular as shown.

The bar 42 may be attached at its ends to the bars 13 of a frame, just as shown in Fig. 18, and the lever 45 may be latched in its lateral position for stacking the receptacles, by providing spring latches 47 fastened to one of the frame bars 12 with the loose end 48 of the latch permitting the farther end 49 of the lever to slip into said latch, in the position shown in Fig. 19. In Figs. 18, 19 and 21, the clamping lever is illustrated as having a tip of some yielding material such as rubber for engaging the surface of the supporting wall on which the structure is to be used, said tip is marked 50 in these views, but it is to be understood that any one of these levers may be provided with said tips.

It is generally quite advantageous to provide the side of the frame nearest the wall edge with two engaging hooks having the same number of standards 14, but the op-

posite side of the frame may well be provided with but one such hook, which form is shown in Fig. 22 of the drawings where a single hook 51 is carried by one side of the frame.

The frames thus far described are shown as being detachable from the receptacle, but in Fig. 23 I have shown a frame secured fixedly to the bottom of the receptacle. Here, parallel bars 52 are secured at their ends to the tray bottom by means of an angle strip at each end, so that said strip has a downwardly-bent foot 53 for supporting the tray on a horizontal surface when necessary. The clamping bar 54 in this form is attached to the bars 52. The lever and sleeve is mounted upon the bar 54 just as in the manner shown in Fig. 8.

It is not essential that a lever and a sliding member for the clamping bar be provided in separate parts, and I have shown in Figs. 20 and 21 a combined lever and adjustable clamp member which is adapted to fit adjustably the clamping bar 55. The lever 56 is hollow, has a reduced outer end 57 for engaging the wall, and has integral with it at the upper end, a clamp member 58 extending at right angles from the main lever 56. The said member 58 has a rear shoulder 59, and a raised cross bar 60 forward of the said shoulder and spaced therefrom, said clamp member 58 comprising side plates 61 integral with the side plates 62 of the lever 56 and forming together an L-shape plate on either side of the member 58. The bar 60 is integral with the said side plates 61 but is spaced from said shoulder 59 leaving an opening 63 therebetween rectangular in shape to receive therein the said bar 55 upon which the combined lever and clamp member is mounted.

The lever 56 has a plate 64 serving as a back strip integral with the side strips 62 and extending upward to the shoulder strip 59 and downward to the lowermost tip of 57. The side strips 62 have their forward edges folded or bent in at 65 to form together a forward integral plate extending over the major part of the length of the lever 56 only leaving an open space at the upper end thereof, as shown in Fig. 21. This front plate 65 is provided with a T-shaped slot 66 therein which, when the lever 56 is lifted upward into inoperative position adjacent the bar 55, will register normally with an elongated button 67 mounted on the lower surface of 55 by means of a stem 68. When the button 67 has entered the slot 66, a sliding movement of the lever on the bar 55 will clearly lock the lever in raised position, thus providing for folding the levers of this form preparatory to stacking a series of the trays, as shown in Fig. 3.

The bar 55 of Fig. 21 is shown as flat and rectangular in section, but it may have

other forms in cross section, just so the same is adapted to be inserted in the opening 63 of the lever 56.

The various forms for mounting a receptacle upon a narrow supporting edge of a wall are somewhat different as to structural details, but have a generic structure and function, that of combining a frame of metal bars attachable to a receptacle with a lever structure provided with means for engaging one of the cross bars of said frame and providing for ready adjustment of the lever element on the cross bar. Applicant is believed to be the real inventor of this structure.

While the tips 50 are shown in the drawings as applied only to the ends of a lever, it is to be understood that such protective means may be applied to the lower end of any part of the illustrated mechanism, as for example to the legs 14 or any other supporting part of my device.

No limitation is intended as to the particular shape of the receptacle to which my support device is to be applied, other than that it is to be provided with some peripheral rim part 10 usually shaped from the material used for the bottom plate, ordinarily by stamping. But what I do claim and desire to secure by Letters Patent is—

1. In a device of the class described, a receptacle support frame, a cross bar non-circular in cross section included therein, a sleeve member fitting said bar and slideable lengthwise thereof, and a swinging leg member pivoted at one end thereof to said sleeve member for movement from and toward the latter, whereby the leg member may be thrown downward from said frame into active position and folded upward on said pivots to a position approximately parallel with the bottom of a receptacle for readily stacking a plurality of receptacles one upon another.

2. In a device of the class described, a receptacle support frame including therein parallel spaced bars connected with a receptacle and a hollow cross bar attached at its ends to said spaced bars, a sleeve member slideable on said cross bar telescopically therewith and including downwardly extending spaced ears thereon, the bar and sleeve being non-circular in cross section, a brace member pivoted to said ears for movement in a plane substantially at right angles to said receptacle bottom, a portion of said brace member extending rearwardly of said sleeve beyond the rear edge of the sleeve so that said extending portion will clamp the said hollow bar when force is applied to the lower end of the brace member in a direction to lower the same on its pivot.

3. In a support device for receptacles, a frame connected with said receptacle and in-

cluding a cross bar attached at its ends, the intermediate portion being free, a slideable sleeve member enclosing said cross bar and having downwardly extending spaced ears, the sleeve member and cross bar being non-circular in cross section, a brace bar having parallel flange portions lengthwise of the main portion of the brace bar and said flanges pivoted to said ears, so that the upper edge of said main portion will contact said cross bar when the brace member swings downward by gravity, but will be released therefrom when the brace member is raised toward the said bar.

4. In a support device for holding receptacles upon the upper edge of a vertical wall, a frame comprising spaced bars having their ends connected by cross bars forming a parallelogram, said ends being bent downward for a limited length, hook members connected to said bent ends in a vertical position, the upper ends of the hooks being bent inward to detachably engage the rim of a receptacle and the lower ends bent slightly outward to form standards for supporting the receptacle when the latter is to rest on a horizontal surface, an intermediate bar connected to said cross bars between said spaced bars, a slideable sleeve enclosing said intermediate bar and having downwardly extending spaced ears, the sleeve and intermediate bar being non-circular in cross section and a brace member having parallel flanges projecting from a flat portion lengthwise of the member, the flanges being pivoted at one end to said ears, so that lowering of the brace member will lock the same in fixed position on the intermediate bar, and lifting the brace member on its pivot will release the sleeve for sliding movement on the intermediate bar.

5. In a device of the class described, a frame for detachably engaging a receptacle comprising a cross bar mounted underneath the receptacle, a sleeve member mounted on said bar and comprising a plate bent angularly about an axis coinciding with the axis of the bar, a portion of said plate having lateral edges extending in parallelism away from the receptacle to form pivot ears, the sleeve member and cross bar being non-circular in cross section and a brace member comprising an elongated metal plate having its lateral edges bent at right angles to the main portion thereof and pivoted at one end to said ears whereby the brace member may be swung on said pivots toward or away from said bar.

6. In a support device for receptacles, a frame connected with said receptacle and including a hollow cross bar mounted upon its ends, a slideable sleeve member enclosing said cross bar and having downwardly extending ears, the sleeve member and cross bar being non-circular in cross section, a brace mem-

- ber comprising an elongated metal plate having its lateral edges each bent in parallelism at an angle to the main portion thereof to form flanges, the upper ends of 5 said flanges being broadened to enable the portions of the latter farthest removed from the main portion to serve as pivotal portions for mounting the brace member, said portions being pivoted upon said ears, and 10 the upper edge of said main portion of the plate extending rearwardly of the sleeve member so that it may engage the cross bar when the brace member is swung on its pivots away from the receptacle.
- 15 7. In a device of the class described, a receptacle support frame including parallel spaced bars mounted beneath the receptacle and a cross bar connecting said spaced bars, a plurality of downwardly-directed extensions forming a fixed part of said spaced bars, and a swinging leg member comprising a brace portion and a sleeve portion, the latter mounted upon said cross bar for longitudinally slidable movement thereon, the 20 sleeve and cross bar having means preventing relative rotation thereof, and the brace portion being pivoted upon under-hanging extensions of the sleeve, and having a part extending beyond the outline of the sleeve to permit engagement with the cross bar, 30 whereby the receptacle may be positioned on the upper edge of a vertical wall, and the latter clamped between the brace portion on one side and the said downwardly-directed extensions on the other. 35
8. In a device of the class described, a receptacle support frame including therein a hollow cross bar of non-circular cross section mounted underneath the receptacle and having a slot in its wall on its face 40 nearest the receptacle and extending lengthwise of the bar, a sleeve member of a cross section fitting the said cross bar and having a longitudinal slot on its face farthest from the receptacle, and slideable upon the said cross bar, and a swinging leg member pivoted at one end to said sleeve member beneath and somewhat spaced from the said cross bar whereby the pivoted end of the member may clamp the bar when turned 45 downwardly away from the receptacle, but be freed from said clamping action when the opposite end of the sleeve member is raised toward the receptacle. 50

In witness whereof I have hereunto set 55 my hand this 15th day of December, 1926.

PAUL W. CURTIS.
